DESIGN FOR A DISPLAY FIXTURE UNIT

Peter V. Martino, Long Island City, N. Y.

Application December 18, 1945, Serial No. 126,988

Term of patent 7 years

(Cl. D80—9)

To all whom it may concern:

Be it known that Peter V. Martino, a citizen of the United States of America and resident of Long Island City, State of New York, has invented a new, original, and ornamental Design for a Display Fixture Unit of which the following is a specification, reference being had to the accompanying drawing, forming part thereof, in which,

Fig. 1 is a top plan view of a display fixture unit embodying my new design;

Fig. 2 is a front elevational view thereof;

Fig. 3 is an end elevational view as viewed from the left side of Fig. 1;

Fig. 4 is an end elevational view thereof as viewed from the right side of Fig. 1;

Fig. 5 is a rear elevational view thereof.

I claim:

The ornamental design for a display fixture unit, substantially as shown.

PETER V. MARTINO.
